ABSTRACT OF THE DISCLOSURE

Process for the noncatalytic thermal hydrodealkylation of alkyl-substituted aromatic hydrocarbons which comprises preheating hydrocarbon oils containing alkyl-substituted aromatic hydrocarbons or hydrocarbon oils containing alkyl-substituted aromatic hydrocarbons and non-aromatic hydrocarbons together with from 2 to 10 mols of hydrogen per mol of the starting hydrocarbons, and passing the mixture through two or more reaction zones, the first of said reaction zone being a back mixing-type reactor and a second or the subsequent reaction zones being piston flow-type reactors.

Field of the invention

This invention relates to an improvement in the process for the noncatalytic thermal hydrodealkylation of hydrocarbon oils containing alkyl-substituted aromatic hydrocarbons or hydrocarbon oils containing alkyl-substituted aromatic hydrocarbons and nonaromatic hydrocarbons.

For brevity's sake, alkyl-substituted aromatic hydrocarbons may be referred to simply as "alkyl aromatics" hereinafter.

Description of the prior art

Normally, the reaction in which aromatic hydrocarbons are produced by the hydrodealkylation of alkyl aromatics is highly exothermic. The amount of heat generated in the reaction varies considerably depending upon the type and number of alkyl groups present on aromatic nucleus of the starting alkyl aromatics, and further upon the relative configuration of alkyl groups, i.e., o-, m-, p-positions, when two or more alkyl groups are present on the aromatic nucleus.

The heat of reaction in the hydrodealkylations of toluene and xylene, i.e., most conventional types of alkyl aromatics, are approximately 12 Kcal./mol and 23 Kcal./mol, respectively.

When a fraction containing nonaromatic hydrocarbons such as paraffinic, naphthenic and olefinic hydrocarbons in addition to aromatic hydrocarbons is used as a starting material, these nonaromatic hydrocarbons are subjected to a thermal hydrogenolysis and they are decomposed to light hydrocarbon gases having 1 to 2, sometimes 3, carbon atoms.

The heat of reaction in the thermal hydrodealkylation of these nonaromatic hydrocarbons is several times as great as in the hydrodealkylation of alkyl aromatics.

In this instance, the amount of heat of reaction is dependent upon the number of carbon atoms and the molecular structures of these nonaromatic hydrocarbons. For example, in the hydrodealkylation of nonaromatic hydrocarbons of the general formula, C_nH_{2n+2} , wherein n represents numbers of 6 to 8, there is generated a large amount of heat of reaction as great as approximately 45-55 Kcal./mol.

Thus, one of the measures adopted in the prior art processes in order to remove such a great amount of heat of reaction so as to maintain the reaction system at a

desired level of reaction temperature has been to incorporate a material such as benzene which is substantially inert in nature to the hydrodealkylation into the starting alkyl aromatics or a hydrocarbon mixture containing the same, preheating the reaction mixture up to a required temperature, and introducing the same subsequently to the reaction zone. In this instance, the extraneous benzene may be incorporated into the starting reactants from the beginning of the reaction as above, or, it is possible that benzene formed in the reaction system by the hydrodealkylation of alkyl aromatics serves as a diluent as it is.

Another countermeasure to deal with the controlling of reaction temperature has been the provision of side stream supplying ports at different points along the reaction zone, by which a cooling agent is ejected into the reaction zone so that the rapid temperature rising may be prevented to maintain the temperature in the reaction zone at a desired level. In this method, starting hydrocarbon oil, liquid hydrocarbon products, hydrogen or hydrogen containing gas are normally used as cooling agents.

Although these methods mentioned above are fairly successful in avoiding the rapid rising of the reaction temperature, the economy of overall hydrodealkylation of alkyl aromatics is greatly degraded due to the complications in the equipment employed and difficulty in operation.

The first above-mentioned method in which a material inert in nature to the hydrodealkylation reaction is incorporated into the reaction system has a great drawback in that it leads to the decrease in the partial pressure of alkyl aromatics to be hydrodealkylated, which in turn gives rise to the decrease in the reaction rate. As a result, the method necessitates larger capacities for the entire equipment including the reactor, preheater, gas-liquid separator, purifying unit, etc., for the production of a given amount of product, causing increase in the fixed cost per unit amount of the product, thus, the method is greatly handicapped from the economical point of view.

The second above-mentioned method in which the controlling of temperature is accomplished by the injection of a cooling agent from the side stream supplying ports provided along the reaction zone also, as in the first method, inevitably requires the enlargement of the equipment stemmed from the use of surplus gas, i.e., cooling agent. Moreover, since the fluctuations in the temperature and the flowing amount of the cooling agent in this method lead to the change in the behavior of reactants in the reaction zone, the operation in this method has been extremely difficult.

Summary of the invention

It is, accordingly, an object of this invention to provide a process for the noncatalytic thermal hydrodealkylation of alkyl aromatics in a high efficiency free from inconveniences accompanied by the prior art processes.

Heretofore, the hydrodealkylation reaction has been normally conducted in an adiabatic piston flow-type reactor. In order to proceed the hydrodealkylation in such a reactor, it is absolutely necessary to preheat the starting gas up to a temperature at which the hydrodealkylation reaction is initiated, e.g., 580-650° C., at the inlet of the reaction zone. Once the hydrodealkylation reaction is initiated, the reaction proceeds automatically thereafter with its own exothermic heat of reaction.

However, since the reaction rate is normally an exponential function of the temperature, the reaction temperature in the piston flow reaction zone rises rapidly with respect to the flowing direction of the reaction fluid, after the reaction is initiated.

The upper limit of the temperature rising in such adiabatic reaction zone is primarily determined by the amount of heat of reaction and the specific heat of the reaction fluid. The value varies in a wide range depending upon the composition of the starting material used. For example, in the hydrodealkylation of toluene, it is approximately 120° C., and, in the hydrodealkylation of a fraction containing nonaromatic hydrocarbons, it can be as high as 150–300° C. Thus, if the temperature of the starting gas is raised up to a temperature which is sufficient to initiate the hydrodealkylation reaction, e.g., 580–650° C. or higher, at the inlet of the reaction zone of the adiabatic piston flow-type reactor, then, the temperature at the outlet of the reaction zone is inevitably raised up to as high as 800–950° C.

On the other hand, the order of reaction in the hydrodealkylation is 1 with respect to the partial pressure of alkyl aromatics and 0.5 with respect to the partial pressure of hydrogen. Thus, the higher the reaction pressure, the more desirable from the standpoint of the order of reaction, and in general, the operation is carried out under the pressure of from 1 to 60 kg./cm.² (gauge), and most preferably from 10 to 40 kg./cm.² (gauge).

Accordingly, in the conventional hydrodealkylation reaction practised heretofore, it is very likely that the reactor employed in the reaction is exposed to such a high pressure and a high temperature, i.e., 800–950° C., as described above. It is readily appreciated that the economical procurement of materials for equipment to withstand such high temperature and pressure is by no means an easy matter.

Moreover, as the reaction temperature becomes higher, the formation of by-produced dealkylation-condensation product is increased with result in the lowering of selectivity. Thus, there have been proposed various methods of preventing the rapid rising of reaction temperature in the hydrodealkylation equipment heretofore. Nevertheless, these proposed methods are accompanied by such inconveniences as described above.

We have found that the hydrodealkylation of alkyl aromatics can be conducted efficiently free from inconveniences accompanied by the conventional processes by conducting the hydrodealkylation reaction in at least two reaction zones, the first reaction zone comprising a back mixing-type reactor such as a hollow cylinder surrounded by a heat insulating material, and a second or the subsequent reaction zone being a conventional adiabatic piston flow-type reactor surrounded by a heat insulating material and connected in series to said first reaction zone.

That is, in accordance with this invention, there is provided a process for the noncatalytic thermal hydrodealkylation of alkyl aromatics which comprises preheating the alkyl aromatics or a hydrocarbon fraction containing the same and nonaromatic hydrocarbons together with from 2 to 10 mols per mol of said starting oil, and passing the resultant mixture through two or more reaction zones, said first reaction zone being a back mixing-type reactor and said second or the subsequent reaction zone being adiabatic piston flow-type reactors.

The first reaction zone in the process of this invention is not an adiabatic piston flow-type reactor commonly used heretofore but an adiabatic back mixing-type reactor in which the reaction fluid is completely mixed in the reaction zone. By using this back mixing-type reactor, the temperature in the reaction zone may be stabilized at the desired level without any rapid changes as in the piston flow-type reactor. Normally, in the adiabatic reaction system, the temperature difference between the inlet and outlet is constant, irrespective of the flowing condition of the reaction fluid in the reaction zone, i.e., the difference is invariably constant regardless of the type of reaction zone. However, there is a remarkable difference between the piston flow-type reactor and the back mixing-type reactor in that the former essentially requires high

temperature at the inlet of the reaction zone which is sufficient to initiate the hydrodealkylation reaction, whereas in the case of the latter no such arrangement is required. The reason is that in the back mixing-type reactor the gaseous reactants contained therein are completely mixed together and the temperature is maintained at a certain level. Thus, in the back mixing-type reactor, it is possible to regulate the temperature in the reaction zone so as not to unnecessarily exceed the temperature at which the reaction is initiated. In the back mixing-type reactor, since the temperature in the reaction zone is the same as that at the outlet thereof, the starting material may be supplied to the inlet of the reaction zone at a temperature which is lower by the difference between the temperatures at inlet and outlet of reaction zone which is determined by the heat of reaction and the specific heat of the reaction fluid. Therefore, for example, assuming that a temperature of the reaction zone at which the reaction is initiated is 650° C., the temperature at the inlet of the reaction zone can be lowered to the order of 400–500° C. In other words, by using the back mixing-type reactor, the reaction can be conducted at lower temperature, e.g., lower by 200–300° C., as compared with the use of the piston flow-type reactor, and furthermore, the temperature at the inlet of the reaction zone can also be lowered to the same degree. Consequently, the reaction can be operated at an optional temperature within the range including a lower limit of 580° C. and an upper limit of 850° C. which is restricted from the standpoints of material for the equipment and the occurrence of undesirable side reactions.

The point mentioned above not only enables to reduce the burden imposed on the preheater in the reaction which calls for a heavy pressure and a high reaction temperature but also to suppress the reaction in the preheater to the lowest minimum and facilitates the easier control of temperature at the inlet of the reaction zone. In addition, there are brought about a number of advantages from the commercial points of view in that the equipment can be made less expensively; that the operation can be made easier due to the leveling of the temperature in the reaction zone; and that the selectivity of the reaction can be enhanced due to the suppression of formation of by-produced dealkylation-condensation products, as a result of proceeding of the reaction in the low temperature region. Furthermore, the adiabatic back mixing-type reactor has an advantage in that the capacity of the reactor can be made smaller, e.g. 1/2–1/5, as compared with that of the piston flow-type reactor, up to a certain rate of conversion.

However, once the reaction is proceeded up to a certain degree, the reaction becomes nearly an isothermal reaction even in the piston flow reaction, and the back mixing-type reactor requires greatly prolonged residence time to obtain a high conversion beyond the certain level. Thus, if the reaction were to be carried out up to the desired rate of conversion in the back mixing-type reaction zone alone, the size of the reactor should be very large.

In addition, when nonaromatic hydrocarbons are contained in the starting oil, some of them are short circuited because of the wider distribution of residence times and they are discharged unreacted without being decomposed to light hydrocarbon gases having 1–3 carbon atoms. These unreacted nonaromatic hydrocarbons give an azeotropic mixture with benzene produced in the hydrodealkylation, which may not be separated by distillations.

The remaining of such azeotropic mixture in the final product, of course, leads to the degraded purity of the product benzene which gives rise to lowering of the freezing point, widening of the distillation range, deterioration in the sulfuric acid coloring test and so forth.

In order to overcome this problem, it is necessary that those nonaromatic hydrocarbons are converted completely

in the reaction zone to light hydrocarbons which can be easily separated from the liquid product by a liquid-gas separator.

We have found that nonaromatic hydrocarbons are converted completely to light hydrocarbons by arranging the second or subsequent adiabatic piston flow-type reaction zones connected in series with the back mixing-type reaction zone of a first reaction stage. In the adiabatic piston flow-type reaction zone, the distribution of residence time is narrowed and no short circuiting of reactants occurs, in other words, there is provided an equal residence time for any part of any reaction fluid. Thus, as the reaction is proceeded up to a certain extent and the concentration of reactants in the reaction fluid is decreased, the back mixing-type reaction zone requires quite large capacity for the reactor in order to carry on the reaction beyond that point, whereas in the piston flow-type reaction zone where no short circuiting takes place can do with the smaller capacity for the reactor as compared with the back mixing-type reaction zone.

From such point of view, in the process of this invention there is provided a second and the subsequent stages of the piston flow-type reaction zones and, by so arranging, when the unreacted alkyl aromatics discharged from the first stage are hydrodealkylated up to the desired rate of conversion, nonaromatic hydrocarbons contained in the starting oil are converted completely to light hydrocarbon gases. Thus, there is brought about a remarkable advantage by the combination of the back mixing-type reaction zone of the first stage and the piston flow-type reaction zones of the second and the subsequent stages.

In carrying out the back mixing in the first stage of the process of this invention, the provision of a stirrer to the reactor is desirable as in the conventional liquid-phase reactor. However, the stirring of high temperature gas under such a high pressure as in the instant reaction, e.g., 1-60 kg./cm.² (gauge), and preferably 10-40 kg./cm.² (gauge), is not an easy matter due to the mechanical difficulty involved in the insertion of the stirrer into the reactor. Therefore, in the process of this invention, it is suitable to adopt a jet-type internal recycling reactor utilizing kinetic energy of moving gas or a way of internal mixing by feeding a fluid from the tangent direction of the cylinder along the inside wall thereof.

The reactors which may be used in the process of this invention in the second and the subsequent stages can be of the conventional adiabatic hollow cylinder-type condition. If necessary, hydrogen as a cooling agent may be fed to the reaction mixture between the first and the subsequent stage reactors.

The starting materials which may be used in the process of this invention are alkyl aromatics or hydrocarbon fraction containing the same. They include alkyl aromatics such as toluene, xylene, ethylbenzene, propylbenzene, methylethylbenzene, trimethylbenzene and diethylbenzene, and hydrocarbon fractions containing nonaromatic hydrocarbons such as paraffinic, naphthenic and olefinic hydrocarbons.

Hydrogen gas containing impurities such as light hydrocarbon gases such as methane, ethane and propane, carbon monoxide and carbon dioxide may be used in the process of this invention without giving any adverse effect so long as the purity is more than 40% by volume, and preferably more than 60% by volume.

The amount of hydrogen to be fed to the reaction zone is more than one mol, and preferably from 2 to 10 mols, per mol of starting oil. The use of less than 2 mols of hydrogen per mol of the starting oil leads to the decrease in the rate of dealkylation and increases the formation of tarry material which is by-produced in the hydrodealkylation reaction thus decreasing the yield of aromatic hydrocarbons. In addition, it sometimes gives rise to the clogging of reactor due to the formation of carbon. However, the use of excessive amount of hydrogen, e.g., more than 10 mols per mol of the starting oil

gives no particular increase in the effect thus it is disadvantageous from the economical point of view.

The temperatures in the reaction zones in the process of this invention are preferably from 580° C. at which the reaction is initiated to 800° C., and the pressure is 1-60 kg./cm.² (gauge), and preferably 10-40 kg./cm.² (gauge) from the economical standpoint, though the higher the pressure, the more advantageous theoretically as described above.

In summary, by the provision of two or more separated reaction zones in the hydrodealkylation process according to this invention, there are brought about many advantages mentioned below all of which contribute to the economical hydrodealkylation of hydrocarbons on a commercial scale, namely:

- (1) The control of temperature in the highly exothermic reaction can be made easier,
- (2) Starting material can be fed to the reaction zone at a low temperature,
- (3) Recycling of product for the controlling of reaction temperature is not necessary,
- (4) No jetting of hydrogen or inert gas as cooling agent for the control of temperature in the reaction zone is required,
- (5) Dealkylated product of high purity can be obtained, and
- (6) Reactor of a smaller capacity may be conveniently used.

Description of preferred embodiments

This invention may be explained more fully in the following examples. However, it should not be construed that the examples restrict this invention as they are given merely by way of illustration:

EXAMPLE 1

Cracked residue by-produced in the steam cracking of naphtha in the production of ethylene was hydrogenated and the product was used as a starting material. The material had a boiling range of approximately 65-180° C. and the composition was as shown below:

	Aromatic hydrocarbons:	Percent by weight
	Benzene -----	25.5
	Toluene -----	21.0
	Xylene -----	15.7
45	Nonaromatic hydrocarbons -----	37.8
	Total -----	100.0

After the starting oil mentioned above was mixed with 50 6 mols of hydrogen pressurized at about 23 atmospheres per mol of said starting oil, and heated in a preheater up to 510° C., the resulting mixture was introduced to a first stage, i.e., a back mixing-type reaction zone and subsequently to a second stage, i.e., piston flow-type reaction zone. When 85% of alkyl aromatics were converted, a temperature at an outlet of the first reaction zone was 670° C. and that of the second reaction zone was 680° C. The composition of the resulting product was shown in Table 1 shown hereinafter.

COMPARATIVE EXAMPLE 1

The same material and hydrogen as used in Example 1 were mixed according to the same procedures as described therein and heated up to 630° C. in the preheater, and 65 the resulting mixture was fed to piston flow-type reaction zone which corresponds to the second stage in Example 1. When 85% of alkyl aromatics were converted, the temperature at an outlet of the reaction zone was 800° C. and the composition of the resulting product was shown in 70 the Table 1 appearing hereinafter:

COMPARATIVE EXAMPLE 2

The same material and hydrogen as used in Example 1 were mixed and heated according to the same procedures as described therein and the resulting mixture was fed to

a back mixing-type reaction zone which corresponds to the first stage in Example 1. When 85% of alkyl aromatics were converted, the temperature at an outlet of the reaction zone was 680° C. and the composition of the resulting product was shown in the following Table 1 which also shows the results obtained in Example 1 and Comparative Example 1:

TABLE 1.—COMPOSITION OF PRODUCTS¹

Products	Example 1	Comparative 1	Comparative 2
Benzene.....	47.3	42.0	47.2
Toluene.....	5.2	5.2	5.3
Xylene.....	1.0	1.1	1.0
Non-aromatics.....			5.0
Tarry matter.....	3.3	8.2	3.2

¹ Percent by weight based on the weight of the starting oil.

As can be noted from the above, in Comparative Example 1, the reaction temperature was raised up to 800° C. and the formation of tarry matter was increased, which in turn, decreased the yield of benzene.

In Comparative Example 2, although the formation of tarry matter was decreased due to the lower reaction temperature, there is a drawback in that it gives more non-aromatics which have not been decomposed.

In the process of this invention, on the other hand, the formation of tarry matter is decreased due to the lower reaction temperature and nonaromatics are decomposed completely and ceased to exist.

EXAMPLE 2

The hydrodealkylation reactions of toluene were conducted by using three different types of reactors, i.e., (1) an adiabatic piston flow-type reactor, (2) an adiabatic back mixing-type reactor, and (3) a combination of an adiabatic back mixing-type reactor and an adiabatic piston flow-type reactor.

The reactions were conducted under conditions including a feed temperature of 630° C., a feed pressure of 25 atmospheres and a feed rate of 92 kg./hr. of toluene, and the capacities of these various types of reactors required to convert 90% of toluene fed were as follows:

Type of reactor	Required capacity (m. ³)	Relative ratio of required capacity
Adiabatic piston flow-type.....	1.45	1.92
Adiabatic back mixing-type.....	1.08	1.43
Combination of adiabatic back mixing-type and adiabatic piston flow-type.....	0.755	1.00

As can be noted from the above, the prior processes require larger capacity for the reactor by 1.4-1.9 times as compared with the process of this invention.

We claim:

1. A process for the noncatalytic thermal hydrodealkylation of alkyl-substituted aromatic hydrocarbons which comprises preheating hydrocarbon oils containing a member selected from the group consisting of alkyl-substituted aromatic hydrocarbon and a mixture consisting of alkyl-substituted aromatic hydrocarbon and nonaromatic hydrocarbon, together with hydrogen, and passing the preheated mixture through at least two independent reactors arranged in series and maintained at hydrodealkylating conditions, the first of said reactors being a back mixing-type reactor to effect substantially complete mixing of the components of the preheated mixture with the reactants and stabilization of the temperature in said first reactor, and each subsequent reactor being a piston flow-type unpacked reactor.
- 10 2. A process according to claim 1 wherein said hydrogen is used in an amount of 2 to 10 mols per mol of the starting alkyl-substituted aromatic hydrocarbons, the temperatures of the reaction zones are from 580 to 800° C., and the pressure is from 1 to 60 kg./cm.² (gauge).
- 15 3. A process according to claim 1, further comprising contacting the reaction mixture passing from the first reactor to the next reactor with an additional source of hydrogen to cool the mixture.
